UNITED STATES PATENT OFFICE.

NORMAN E. JOHNSON, OF CHICAGO, ILLINOIS, ASSIGNOR TO CHICAGO RHOPAC PRODUCTS COMPANY, OF CHICAGO, ILLINOIS, A CORPORATION OF ILLINOIS.

MOLD FOR MAKING PACKING OR THE LIKE.

Application filed October 10, 1923. Serial No. 667,696.

My invention belongs to that general class of devices known as molds and relates more particularly to a mold adapted for the making of packing rings in a plurality of sections suitably secured together for convenience in assembly and application.

The invention has among its objects the production of a device of the kind described that is simple, convenient, compact, efficient and satisfactory for use wherever found applicable. It has particularly as an object the saving of time and labor in making the rings, as well as producing a more satisfactory ring.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Figure 1 is a plan view of my improved mold;

Figure 2 is a sectional view taken substantially on line 2—2 of Figure 1;

Figure 3 is a sectional view taken substantially on line 3—3 of Figure 2;

Figure 4 is a sectional view taken substantially on line 4—4 of Figure 3, the upper section of the mold being also shown to better illustrate the invention; and

Figure 5 is a perspective view of a cast or molded ring.

Referring particularly to Figure 5, I have shown a packing ring consisting of the desired number of sections 1 which may be secured together by the connecting members 2 of soft wire or equivalent connecting means. The mold shown consists of a part 3 which is provided with a recess or cavity 4 of the desired size and shape to cast the ring. The part 3 may be of any suitable material and obviously the recess 4 may vary in contour depending on the particular article to be molded. As shown, part 3 is mounted on a spindle or support 5 and maintained from rotation thereon in any suitable manner, for example by a key 6 or its equivalent.

In making a ring of a plurality of sections, I prefer to provide a plurality of what

may be termed partitions or separators 7 which are arranged in the grooves 8 on the part 3 and extend across the recess 4. These may be secured in place in any suitable manner, the preferred construction being to attach them to a ring 9 by means of the rivets 10 or the equivalent. They are thus maintained assembled and are not easily displaced and may be interchangeably employed in molds, slightly greater or smaller molds. The members shown are provided with notches 11 in which the wires 2 may be placed before pouring the metal. It will be noted that the separators 7 divide the mold cavity into a plurality of matrices. Arranged to cooperate with the part 3 of the mold is a part 15 which is formed with a gate opening 16 for each section so that the molten metal may be poured into the recess 4.

It will be noted by referring to Figure 2, that I prefer to make the edge 17 at the bottom of the opening 16 substantially sharp. The member 15 is rotatably or movably mounted on the spindle 5 and may be provided with one or more operating handles or lugs 18.

In using the mold the wires 2 are placed as shown and thence the part 15 applied. The metal may then be poured through the gate openings 16, flowing into the recesses 4 where it hardens, forming the packing rings.

Obviously, some of the material will generally partially fill the gate openings as indicated at 16', this being what is generally termed a gate. Before removing part 15 from the mold part 3 to remove the cast ring, part 15 is partially rotated on the spindle, thereby severing all gates which, upon turning over the part 15, will drop out of the gate openings and the cast ring may then be readily removed from the mold. Obviously, it is immaterial as to which mold part is moved relatively the other, but it is generally more convenient to make the part 15 movable and prevent part 3 from moving. If desired part 3 may be moved from the spindle or the cast ring may be lifted out without removing part 3.

I have shown the notches 11 of a size to receive the wire 2, the ends of the wire being turned down so as to be imbedded in the body of the material. Obviously, if the wire is not employed the metal itself may flow over and connect adjacent sections. When,

however, this method of connecting the sections is employed, I prefer to make the notch somewhat larger and in some cases provide a plurality of notches.

6. Obviously, when the gates are removed in the manner described the shearing off of the same takes place practically simultaneously with the removal of part 15, so that when the ring is removed from the mold it is a 10 completed ring, requiring no further operations other than to assemble or pack, the same being usually assembled with rubber or equivalent rings, not necessary to describe in detail herein. The time and labor in removing the gates by breaking or otherwise and filing or scraping down the surface so as to produce a finish, is entirely obviated, and in addition a more finished product is secured, as the gates are cut off flush and 15 assembled with the face of the ring, thereby making the ring more efficient and more satisfactory. This may be done before the ring is entirely cooled, thereby making the operation easier and avoiding the handling of hot 20 rings to remove the gates after removal from the mold, or requiring them to accumulate and cool before removing. The device, therefore, has many advantages. Of course, the rings may be cast in any desired number 25 of sections, and while for bearing metal the shearing may be very easily done by hand, for harder materials the part 15 may be operated by power rather than manually. It is not considered, however, necessary to 30 describe this in detail, as it will be obvious to those skilled in the art.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

45. What I claim as new and desire to secure by Letters Patent is:

1. In apparatus for molding metallic packing rings, a mold section having a mold cavity therein, a plurality of partitions arranged transversely of the mold cavity for forming a plurality of independent chambers in the mold cavity, a second mold section revolubly mounted with respect to said first mold section and having a gate for each 50 of said chambers, and means for rotating said second mold section with respect to the first mold section.

55. 2. In apparatus for molding metallic

packing rings, the combination with a mold having an annular recess therein divided 60 into a plurality of circumferentially disposed matrices, of a cover for said mold, said cover being provided with a plurality of gates through which molten metal is poured into the respective matrices and affording 65 shearing edges at the under side of the cover, and means disposed axially of the mold recess for pivoting the cover upon the mold.

3. In apparatus for molding packing rings, a mold section having a mold cavity 70 therein, a plurality of partitions arranged in said mold cavity for forming a plurality of independent chambers, said partitions being adapted to support inserts to be embedded in the packing ring, and a second mold section revolubly mounted with respect to said first mold section when it is operatively engaged therewith and having a gate for each of said chambers.

4. In apparatus for molding packing 80 rings, a mold section having a mold cavity therein, a separable member comprising a plurality of partitions arranged transversely of the mold cavity and dividing the mold cavity into a plurality of independent chambers, and a second mold section revolubly mounted upon and carried by said first mold section and having a gate for each of said chambers.

5. In apparatus for molding packing 90 rings, a mold section having a mold cavity therein, a separable member comprising a plurality of partitions arranged transversely of the mold cavity and dividing the mold cavity into a plurality of independent 95 chambers, each of said partitions being grooved to hold an insert to be embedded in the packing ring, and a second mold section revolubly mounted upon said first mold section and having a gate for each of said 100 chambers.

6. The combination with a mold having an annular recess therein divided into a plurality of circumferentially disposed matrices, of a cover for said mold, said cover being provided with a plurality of gates through which molten metal is poured into the respective matrices and affording shearing edges at the under side of the cover, and means disposed axially of the mold recess for 105 coupling the cover to the mold, said means also serving as a pivot for the cover.

In testimony whereof, I have hereunto signed my name.

NORMAN E. JOHNSON.
